UNITED STATES PATENT OFFICE.

EARL F. BALDWIN, OF GARDNER, MASSACHUSETTS, ASSIGNOR TO AMERICAN FIBRE CORPORATION, OF GARDNER, MASSACHUSETTS, A CORPORATION OF MASSACHUSETTS.

BRAIDING MACHINE.

Application filed February 3, 1922. Serial No. 533,799.

To all whom it may concern:

Be it known that I, EARL F. BALDWIN, a citizen of the United States, residing at Gardner, in the county of Worcester and 5 State of Massachusetts, have invented new and useful Improvements in Braiding Machines, of which the following is a specification.

This invention relates to braiding machines being more particularly designed to braid strands of fiber such as are formed from paper strips and is designed to produce a flat braid wherein, if desired, a plurality of strands arranged side by side in one 15 plane may be woven together as a single strand.

The invention resides more especially in the manner of carrying and moving the strand-carrying spools as well as novel constructions of winding up mechanisms and other advantageous details and combinations of parts as will appear from a description of an embodiment shown in the accompanying drawings in which—

25 Figure 1 is a top plan of the machine.
Figure 2 is a horizontal section on line 2—2 of Figure 3.

Figure 3 is a side elevation.

Figure 4 is a detail elevation at right 30 angles to Figure 3 of the winding up mechanism.

Figure 5 is a section on line 5—5 of Figure 4.

Figure 6 is a section on line 6—6 of 35 Figure 4.

Figure 7 is a side elevation of the winding up feed looking in the direction of the arrow A on Figure 3.

Figure 8 is a rear elevation of the spool 40 holder.

Figure 9 is a vertical section on line 9—9 of Figure 8.

Figure 10 is a fragmentary plan showing 45 diagrammatically the movements of a guide shoe.

Figure 11 is a detail vertical section through the shoe and related parts.

Figure 12 is an isometric disassembled view of the shoe and spool carrier base.

50 Figure 13 is a section on line 13—13 of Figure 3.

Figure 14 shows a portion of the finished product.

Figure 15 is a sectional detail of one end of the shoe and spool holder. 55

The machine comprises a table having a top plate 1 and supporting standards or legs 2 spaced thereabout. Parallel to the top plate and spaced therebeneath is a similar plate 3, these plates being spaced to receive 60 the braiding carrier actuating mechanism as will be described. The plate 1 has cut therethrough a slot formed in a closed path comprising two loops in substantially figure 8 formation, as shown at 4 in Figures 65 1 and 10, which forms a guideway for the shoes 5, the machine as herein shown having three such shoes. The portions of the plate 1 within the loops of the figure 8 trackway are supported from the lower 70 plate 3 by means of posts 6 as indicated in Figure 2. On these posts 6 are journaled disks 7 and 8, the adjacent edges of which overlap as shown in Figure 2. These disks 7 and 8 are formed with peripheral notches 75 9 and 10 for the reception of stems 11 depending from the shoes as shown best in Figure 11.

Each shoe comprises an elongated member 12 pointed at its ends as shown best in 80 Figure 12 which rides within the slot 4. The member 12 is held in position between the side faces of the plate 1 by means of a pair of retaining members or plates 13 and 14 while above the plate 14 is positioned a 85 base member 15 of a spool carrier 16. The members 13, 14 and 15 are held in assembled relation with the member 12 by means of a bolt 17 having an upper portion 18 journaled in the base 15, an intermediate 90 portion 19 of smaller diameter threaded through the members 14, the member 12, and the lower plate 13, and a lower portion formed as the stem 11, these parts being held assembled by means of a washer 20 95 above the base plate 15 and a nut 21 engaging the lower end of the threaded portion. By this construction the shoe is retained in position in the guideway and the spool holder is mounted for pivotal movement relative thereto on the bolt 17. 100

Due to the shape of the guideway it is evident that as the shoe moves therein it is rotated end for end. This rotation of the shoe would cause the strands to be twisted 105 if its motion were communicated to the spool

holder, this twisting causing the braid to be woven in round formation rather than flat as is desired in this machine. In order to counteract this rotation this invention provides means for locking the spool holder to the shoe during the major portion of its traverse but at certain times imparting a reverse rotation to the spool holder to counteract the turning motion of the shoe, thus causing the strands to be presented without twist. For this purpose the retaining plate 14 is provided at opposite sides with notches 23 and cooperating with these notches to lock the spool holder to the shoe is a latch 24. As shown in Figure 11 this latch is pivoted at 25 in a recess 26 in the lower side of the base member 15 and its free end, urged downwardly by a spring 27 seated in a socket therein and reacting against the lower face of the base member, is adapted to engage in one or the other of the notches 23. When the latch is in position in either notch 23 it is evident that the spool holder and shoe are locked against relative pivotal movement. It is necessary that the latch be released twice in each cycle of movement of the shoe so that the spool holder may be turned one half a revolution at each release so that as the shoe is traversed and is turned once completely endwise, the spool carrier is turned one complete rotation in the opposite direction relative to the shoe so as to maintain the strands untwisted.

In order to release this latch a cam 30 is fixed to the upper face of the table plate 1 and is provided with an upstanding tapered edge 31 on which the latch 24 rides so that it is raised up from engagement with the notch 23. When so raised provision is made for turning the spool carrier one half a revolution. This means comprises a hook member 35 pivoted at 36 to the plate 1 and having a curved hook end 37, a separate wear piece 38 of hardened material being preferably inserted in a mating recess in the hook at the base of the portion 37.

The base plate 15 has upstanding therefrom at opposite ends a pair of posts 40 joined at their upper ends by a cross bar 41 (Figures 1, 3, and 10). These posts project somewhat below the lower faces of the member 15 (Figure 15) in position to strike on the curved hook faces 37, each of which is normally held in position to be so engaged by means of a spring 45 engaging at one end a bracket 46 extending outwardly from the table and at the other end at 47 with the rear end of the hook, a stop 48 being positioned on the upper face of the plate 1 to determine the extent of forward movement of the portion 37.

Referring now to Figure 10 the position of the parts is shown in full lines before the post 40 engages with the hook face 37,

succeeding positions being indicated in dotted lines. As the post 40 engages on the hook face 37 this post is held from further motion with the shoe, causing the post 40 to move outwardly as the shoe moves, 70 swinging the hook about its pivot and turning the reel carrier base so that its length extends substantially at right angles to the direction of the shoe movement. At this point the rear end of the hook strikes an abutment screw 50 threaded in a lug 51 at the side of the table. Further movement of the shoe then causes the post 40 to ride down the inclined face 37 completing the half turning movement of the plate 15 relative to the shoe, the spring 45 acting on the hook tending to complete this movement. As the plate 15 resumes its position longitudinally of the shoe the latch 24 springs into the opposite notch 23 thus locking the shoe and spool carrier against relative rotation until the latch is released by engagement with the other cam 30.

In order to insure the motion of the spool carrier sufficiently to bring the notch 23 into position to be engaged by the latch 24 a cam is provided. This cam indicated at 60, is pivoted at one end at 61 to plate 1, and is formed with a curved inner face 62 positioned to engage the side and end faces of the spool carrier base 15 and urge it into proper position relative to the retaining plate 14. The cam 60 is held downwardly against the table plate 1 by means of a bolt 63 passing through an arcuate slot 64 in the free end of the cam member and this end of the cam member is normally urged into position to impinge on the base plate 15 by means of a plunger 65 carried in a socket member 66 fixed to the side of the machine. The plunger 65 is normally urged inwardly toward the cam 60 by means of a coil spring 67 engaging its outer end and reacting between it and an adjusting screw 68 threaded in the outer end of the socket member 66. This insures the complete turning of the spool holder to locking position relative to the shoe even though the hook 35 should fail to entirely complete this action. By this means it is seen that the spool carrier is turned in reverse direction to the shoe in steps of one half a turn each adjacent opposite ends of the looped pathway in which the shoe moves.

The shoe is caused to move in its path by rotation of the plates 7 and 8, the stud 11 being carried in one of the notches 9 and being transferred to one of the notches 10 and vice versa at the point of overlap of the disks, the shape of the guide slot and the shoe being such that the shoe may not continue movement with either of the disks 7 or 8 beyond the overlapping position thereof. These disks are driven by intermeshing gears 70 fixed to the disks 7 and 8, one of

these gears 70 being driven from a pinion 71 fixed to a vertical stub shaft 72 which carries beneath the plate 3 a bevel gear 73. This gear 73 is driven by a bevel pinion 74 fixed to a horizontal shaft 75 to which may be clutched a gear 76. This gear is driven from a pinion 77 fixed to the armature shaft of a motor 78. The motor and the various connecting shafts are carried on a shelf 79 suspended by hangers 80 from the plate 3. The clutch for the gear 76 may be of any suitable form and as shown is controlled by a hand lever 81 to which is pivoted a reach rod 82 connected through a yoke 83 to the clutch shown at 84.

Each reel carrier base 15 is adapted to support a plurality of strand carrying spools, herein three being indicated at 85. Each spool is supported on a spindle and the strand led off therefrom in a manner indicated in Figures 8 and 9. Referring to these figures a bracket 86 is fixed to the upper surface of the base plate 15 and carries upwardly extending therefrom a spindle 87. This spindle is threaded at 88 in a portion of the bracket and a nut 89 is employed to lock the spindle in position. The spool is indicated at 90 and fits down over the spindle 87 for rotation thereon. The upper end of the spindle 87 is formed with a socket 91 in which is positioned a coil spring 92. This spring is adapted to react between the bottom of the socket and the lower end of a plug 93 having a knurled head 94, this plug having a laterally extending pin 95 which may pass through a slot 96 extending lengthwise of the spindle and terminating in a hooked lower end 97 in which the pin may be seated by rotation of the plug relative to the spindle. This serves to retain the spool in position on the spindle. The upper end of the spool is formed with a flange 98 which is circumferentially recessed to receive a ring member 99. This ring member has a series of lugs or teeth 100 thereon having inclined faces 101, these lugs forming ratchet teeth by which the spool may be prevented from rotation on the spindle in a direction to unwind the strand. For engagement with these ratchet teeth to prevent rotation is a latch member 102 which is vertically movable between upstanding jaws 103 of a guide plate 104. This guide plate has a boss 105 depending therefrom which is perforated for the slidable reception of a pin 106 made fast at its upper end in the latch member 102 and extending downwardly below the end of the boss 105. Adjacent the lower end of this pin is a washer 107 supported on a pin 108 passing transversely through the pin 106 and on this washer is supported the lower end of a coil spring 109 reacting against the under face of the guide plate 104. By this means the latch 102 is nor-

mally held seated between the jaws 103, but by lifting the latch member 102 against the tension of the spring 109 it may be removed from between the jaws and turned about the pin 106 as a center out of vertical alinement with the spool. By removing the plug 96 the spool may then be removed from the spindle, this construction permitting ready renewal of the spools as the strand thereon becomes exhausted. The guide plate 104 is supported at the upper end of a pair of guide posts 110 which are made fast at their ends in the bracket 86. Intermediate these posts is positioned a bar 111 having a strand eye or guide 112 therein. The strand from the spool passes through this eye and then beneath a guide roll 113 journaled in a bracket member 114 which is vertically slideable on the guide posts 110. This bracket is normally held in its lowest position on these posts by means of coil springs 115 reacting between the lower face of the guide member 104 and the bracket 114. On tension being exerted on the strand tending to unwind the spool, as the spool is held against rotation by latch 102, the bracket 114 is raised upwardly against the tension of the springs until its upper end contacts with the end of the pin 106 and raises the latch 102 sufficiently to permit the spool to rotate. As the spool is then free to rotate the springs 115 exert a rotating impulse thereon which draws off the material from the spool.

The strands from all the spools pass to a guide member at which the braiding takes place, this guide member being indicated generally at 120 in Figure 3. This member is supported on a transverse bar 121 carried at opposite ends in a standard 122 and an upstanding frame comprising side rails 145 and a cross bar 123, the standard and the frame extending upwardly intermediate the length of the machine and is carried by a sleeve 124 adjustable along the bar 121. This sleeve has an upstanding guide portion 125 in which is vertically slideable a plate 126, a bolt 127 carried by the portion 125 and passing through a vertical slot in the plate 126 providing for such slideable adjustment. The plate 126 has fast thereto a frame member or yoke 127 to the upper end of which is pivoted by a lateral extension 128 a similar member 129. Each of these members carries a roller 130 at its lower end. The rollers 130 are normally held together into close engagement with the various strands forming the braid by means of a cam device shown more in detail in Figures 1 and 13. This device comprises a cam 132 pivoted at 133 to the outer end of a rod 134 which extends through the members 127 and 129 and carries a nut 135 beyond the member 127 to hold it in position. Between the members 127 and 125 a coil spring 136 reacts, this spring surrounding the rod 134. 130

The cam member 132 is formed with a cam face 137 which engages the outer face of the yoke 129 and is provided with a handle portion 138 by which it may be turned into and 5 out of camming relation to this yoke. When the cam is in camming relation the rolls 130 are urged firmly together, but when the handle 138 is pulled outwardly the spring 136 forces the yoke members apart slightly 10 to relieve the pressure on the braid. The braid passes over the rollers 130 and to a driven take-up mechanism supported by the post 123. This mechanism comprises a series of rolls 140, 141, and 142, each roll preferably having a central portion which engages the braid formed of yieldable material such as rubber as shown at 143. The braid passes over the upper roll 140 beneath and 15 between this roll and the roll 141 and then between the rolls 141 and 142, this causing 20 an engagement of the surfaces 143 over a considerable length of the braid so as to increase the frictional holding of the rolls thereon. These rolls are positively driven, 25 intermeshing gears 144 at each end of these various rolls being employed for this purpose. The upper roll 140 has fast thereto outwardly of a pair of spaced rails 145 in which the rolls are journaled, a gear 146 which is driven from a pinion 147 carried 30 by a shaft 148 on the opposite end of which is fixed a worm gear 149. This worm gear meshes with a worm 150 on a vertically extending shaft 151 journaled in a bearing bracket 152 projecting laterally from one of the side pieces 145. This shaft carries at its lower end a gear 153 with which is adapted 35 to mesh a gear 154, the gear 154 being a change gear carried by a shaft 155 (see Figure 2) mounted to slide in an arcuate slot 156 concentric with the plate 8. This gear meshes with the corresponding gear 70, and by substitution of gears of various sizes on the shaft 155, the rate of feed of the 40 rolls may be varied to suit the character of the work. The arcuate slot mounting of the shaft 155 permits gears of various sizes to be adjusted to mesh with the gear 70 and the gear 153. The bars 145 are attached to 45 either side of the post 123.

After passing between the lower rolls 141 and 142 the braid passes through a guide eye 160 in a guide bar 161 (see Figures 3 to 6). The guide bar 161 is mounted to slide in a 50 pair of arms 162 and 163 which project upwardly from a bracket 164 made fast to one side of the frame. These arms 162 and 163 have journaled therein a shaft 165 which projects beyond the arm 163 and has fixed thereto a belt pulley 166 and carries a winding reel 167. A belt indicated at 168 passes about this belt pulley 166, is crossed intermediate its length and passes over a pulley 169 mounted to rotate with the roll 140. Provision is made by which the bar 161 is

moved parallel to the shaft 165 in order to guide the braid as it is wound from one end to the other of the reel. For this purpose the bar 161 has in one face thereof a groove 170, this groove being in the form of an 70 elongated loop extending lengthwise of the bar and within this loop are fixed a series of pins 171 extending outwardly from the face of the bar, these pins being spaced to mesh with a pinion 172. This pinion is carried by a shaft 173 having its end 174 shaped to fit within the groove 170 to be guided for traversing movement thereby. The shaft 173 is fixed within the end of a shaft 174 which is journaled in a yoke 175, 80 the arms 176 of which are mounted for rocking movement on the drive shaft 165 between the arms 162 and 163. Within this yoke the shaft 174 has fixed thereto a bevel gear 177 which meshes with a bevel pinion 178 fixed to the shaft 165. By this construction as the shaft 165 is rotated the gear 174 is rotated causing a transverse movement in opposite directions of the bar 161 by engagement of the pins 171 with the 85 teeth of the pinion 172. As the bar 161 traverses, the gear 172 is held in engagement with the pins 171 by the end of the shaft 174 engaging in the slot 170. As it reaches the end of traverse in one direction the portion 174 riding in the slot 170 causes the yoke 175 to tilt slightly about the shaft 165 as an axis and as the pinion 172 rotates about the end pin of the series it starts the traverse of the bar 161 in the opposite direction. This is 90 illustrated in Figure 5 in which the positions of the pinion 172 with relation to the bar are shown in dotted lines when the shaft 174 engages in upper and lower reaches of the looped groove, these being the positions in which the bar is traversed in opposite directions. By this construction the braid is led evenly throughout the length of the reel 167 as it is wound thereon.

The braid formed by this machine is indicated in Figure 14. As shown this machine has three shuttles each carrying a spool holder having three spools though various numbers of shuttles and spools might be employed as well as additional lobes or loops for the path of travel of each shoe. The strands therefore are let out in three groups of three strands each. By causing a plurality of spools to be carried by each shuttle and causing a relative turning movement between the 110 spool holders and the shoes, all the strands of each group are caused to lie in a common plane and the strands of all the groups are so related as to form a flat braid. The strands of one of these groups are indicated 115 at *a*, *b* and *c*, of the second group by *d*, *e*, and *f*, and the third group by *g*, *h*, and *i*, in Figure 14.

Having thus described an embodiment of this invention it should be evident that 120

many changes and modifications might be made therein without departing from its spirit or scope as defined by the appended claims.

5 I claim:

1. In a machine of the class described, a track arranged in a closed path, a shoe movable along said path, a spool holder pivoted to said shoe, means to lock said holder to said shoe to prevent relative pivotal movement thereof, means for rendering said locking means inoperative at certain positions of said shoe on said track, and means for turning said holder relative to said shoe 10 while said locking means is inoperative.
2. In a machine of the class described, a track arranged in a closed path, a shoe movable along said path, a spool holder pivoted to said shoe, means to lock said holder to said shoe in any of a plurality of said positions to prevent relative pivotal movement thereof, means for rendering said locking means inoperative in certain positions of said shoe on said track, and means for turning 15 said holder relative to said shoe from one to another of said positions while said locking means is inoperative.
3. In a machine of the class described, a track arranged in a closed path, a shoe movable along said path, a spool holder pivoted to said shoe, means to lock said holder to said shoe in any of a plurality of said positions to prevent relative pivotal movement thereof, means for rendering said locking 20 means inoperative in certain positions of said shoe on said track, means for turning said holder relative to said shoe from one to another of said positions while said locking means is inoperative, and means for insuring the locking together of said shoe and carrier in said latter position.
4. In a machine of the class described, a track, a pair of members comprising a shoe movable along said track and a spool holder pivoted to said shoe, a latch carried by one of said members adapted to normally engage in any of a plurality of notches in the other of said members to prevent relative rotation thereof, a cam fixed adjacent said

track for engaging and removing said latch 50 from a notch at a point in the movement of said shoe, and means acting while said latch is removed for turning said holder relative to said shoe into position for said latch to engage in another of said notches. 55

5. In a machine of the class described, a track, a pair of members comprising a shoe movable along said track and a spool holder pivoted to said shoe, a latch carried by one of said members adapted to normally engage 60 in any of a plurality of notches in the other of said members to prevent relative rotation thereof, a cam fixed adjacent said track for engaging and removing said latch from a notch at a point in the movement of said 65 shoe, means acting while said latch is removed for turning said holder relative to said shoe into position for said latch to engage in another of said notches, and means for insuring the proper relative positions of 70 said members to permit the latch to engage said latter notch.

6. In a machine of the class described, a plate having a slot defining a continuous track, a shoe movable in said slot, means 75 comprising a notched plate engaging opposite sides of said plate and fixed to said shoe for retaining said shoe in position, a spool holder pivoted to said shoe, and a latch carried by said holder and engageable in a 80 notch of said retaining plate for locking said holder from pivotal motion relative to said shoe.

7. In a machine of the class described, a track, a shoe movable along said track, a 85 spool holder pivoted to said shoe, means to hold said spool holder against pivotal movement in any of a plurality of relative positions, means for releasing said holding means at predetermined points in the movement of said shoe, means to turn said spool holder relative to said shoe when said holding means is released, and a cam resiliently urging said holder into a succeeding locking 90 position relative to said shoe. 95

In testimony whereof I have affixed my signature.

EARL F. BALDWIN.
